Machinery Corporation, Paterson, N. J., a cor-
poration of New Jersey

Application June 30, 1936, Serial No. 88,214
In Great Britain September 13, 1935

20 Claims.

(Cl. 12—25)

This invention relates to machines for trimming or cutting out work-pieces and is particularly, but by no means exclusively, concerned with machines for thus operating upon shoe-5 soles or similar objects. These are of the class in which a roughly shaped article to be trimmed, or a blank from which an article is to be cut, is clamped upon a pattern, between which and a knife there is relative traversing movement dur-10 ing the operation of the machine, in a path determined by the pattern, to effect the trimming or cutting out.

In machines of the character disclosed in the specification of British Letters Patent No. 421,177 15 to British United Shoe Machinery Company, Ltd., power-operated mechanism is employed to effect relative traversing movement between the pattern and the knife, together with control means for the power-operated mechanism which necessi-20 tates the active use of one hand of the operator in a position of safety during the operating move-25 ment to maintain the mechanism in action. In operating such a machine, it is necessary for the operator to maintain a clutch-controlling handle depressed during the whole of the machine-cycle. This safeguards the operator's right hand. In 30 that machine, however, no means is provided which necessitates the employment of the left hand of the operator during the machine-cycle in such a position as to guard this hand against injury.

An object of the present invention is to provide in machines of the class referred to novel means 35 for controlling the power-operated mechanism, which means comprises a pair of members which necessitates the use for operating them of both hands of the operator and are positioned close together on the machine for convenient and safe manipulation. In an application of Joseph 40 Gouldbourn and Harold E. Elliott for Letters Patent of the United States, Serial No. 22,302, filed May 20, 1935, a similar organization is disclosed and more generically claimed.

In order that the present invention may be 45 more fully understood, it will now be described with reference to the accompanying drawings, in which

Fig. 1 is a right-hand, side elevation of the upper portion of the machine, indicating mainly 50 certain clutch-operating mechanism;

Fig. 2 is a front elevation of the portion of the machine seen in Fig. 1;

Fig. 3 is a plan view of the machine;

Fig. 4 is a plan view, on an enlarged scale, of 55 the clutch-controlling mechanism, and

Fig. 5 shows certain parts seen in Fig. 1 as they appear when viewed from the rear.

The machine has a frame 1 upon which is rotatable a table 11 carrying supporting and actuating mechanism for a rounding knife 135, substantially as disclosed in the previously mentioned British patent. In the present machine, however, the table is driven by single-speed mechanism of the kind disclosed in application for Letters Patent of the United States herein-10 before referred to, instead of by two-speed mechanism, and the driving shaft 5 of the machine extends horizontally rearwardly of the machine instead of transversely. The knife 135 acts upon a blank held between the usual pattern 137 and clamp 139 mounted upon the frame. Secured to the rear of the frame 1 is a rearwardly extending bracket 3 which has a bearing for one end of the driving shaft. The forward end of the driving shaft passes through the frame and is supported 20 in bearings therein. Outside the frame, the driving shaft has secured on it a bevel-pinion 7 which meshes with a bevel-gear 9 on the under side of the table 11. The driving shaft 5 has rotatably and slidably mounted on it, between its 25 bearing on the bracket and the frame, a driving pulley 13. This pulley has at the forward side an internal cone-face 15 which is caused, by forward movement of the pulley along the shaft, to engage with an external cone-face on a member 17 30 secured on the shaft to cause it to be driven. The fact that the driving mechanism is positioned on the rearward end-portion of the shaft insures that the driving belt will be well removed from the operator's vicinity and will offer little ob-35 struction to light falling on the operating position. The pulley 13 is moved along the driving shaft into engagement with the member 17 by upward movement of a wedge 19. This wedge has a vertical face at its rear side bearing 40 against the bracket 3 and at its forward side an inclined face which engages an inclined face on the rear of a block 21 slidably mounted on the shaft 5 rotating freely within it. The front vertical face of the block rests against the rear of 45 the pulley 13, and the wedge 19 moves in a guide-way in the block and thus prevents it from rotating. The wedge is formed at the upper end of a bar 23 (Fig. 5), which at its lower end is pivotally connected to one arm 25 of a wedge-actuating lever secured to the rear end of a horizontal wedge-actuating shaft 27 parallel to the driving shaft 5. The shaft 27 is rotatable in bearings 50 on the bracket 3 and is lower than and at the left of the driving shaft 5, as viewed from the 55

front. It has secured to it near its front end an arm 29, which extends substantially horizontally toward the right, and the under face of this arm is engaged by an arm 31 of an intermediate lever 33 fulcrumed on a horizontal stud 35 secured in the bracket 3. Another arm 37 of the intermediate lever extends to the right and has a face 39 which engages a brake-releasing lever 41 (Fig. 1) hereinafter referred to. A spring 43 connected to the arm 25 of the wedge-actuating lever and to the rear bearing for the driving shaft tends to raise the wedge to move the pulley 13 along the shaft into engagement with the member 17. A stronger spring 45, connected to the arm 37 of the intermediate lever and to the bracket 3, tends to rotate the intermediate lever in a direction to withdraw the wedge 19 and thus relieve the driving pressure between the pulley and the member.

20 The brake-releasing lever 41, with its associated brake-band and plunger mechanism, generally resemble and operate to stop the machine and return the knife 135 to its initial position in a manner similar to the mechanism disclosed in 25 Letters Patent of the United States No. 1,782,494, Woodcock et al., November 25, 1930. Said lever is pivoted to an arm 42 rotatably mounted on the driving shaft 5 and has joined to it one end of a brake-band 47, which passes around a brake-drum 49 secured on the driving shaft 5. The other end of the brake-band is adjustably connected to the fulcrum-stud of the brake-releasing lever. A spring 46 connected to the lever 41 and to the arm 42 tends to swing said lever in a direction to tighten the brake-band on the drum. The arm has pivotally connected to it one end of a plunger 48 which slides in a tubular casing 51 pivoted on the bracket 3. A spring 52 inside the casing 51 surrounds the plunger and bears 40 at one end against a head on the end of the plunger, remote from its pivotal connection to the arm, and at its other end against a cap on the casing. The arrangement is such that when, by the closing of the brake-band 47, the arm 42 is clutched to the drum 49 and moves temporarily with it, the spring 52 is compressed and gradually stops the knife. The spring then expands and returns said knife to its normal position.

50 The intermediate lever 33 is actuated to release the brake and allow the wedge 19 to be moved by its spring 43 upwardly to carry the pulley 13 into engagement with the member 17, by a substantially horizontal, rearwardly extending arm 53, which contacts with the under side of the arm 37 of the lever 33. The arm 53 is pivoted at its forward end to the right-hand side of the machine-frame 1 on a stud 55. This arm is connected by an upwardly extending rod 57 to one arm of a bell-crank-lever 59 fulcrumed upon the frame by a stud 61. The other arm of the lever 59 is coupled by a ball-joint to a forwardly extending rod 63 connected at its forward end to mechanism by which it may be moved rearwardly to actuate the lever 33 and cause the machine to be operated.

65 The greater part of the mechanism for actuating the rod 63 is mounted on a bracket 64 (Fig. 4), secured on the top of an overhanging arm of the frame 1 near the front thereof and over the rotary table, and is enclosed by a casing 65. The rod is connected at its forward end by a ball-joint to a horizontal arm 67 extending laterally of the machine below the frame-arm. The arm 67 is fast upon the lower end of a vertical shaft 75 69 which is rotatable in a bearing in the bracket

64, and the upper end of which extends into the casing 65. The shaft 69 has extending to the right near its upper end an arm 71, to the front face of which is attached a block 73. The arm 67, shaft 69 and arm 71, taken together, may be considered as a clutch-lever through which the driving mechanism is controlled. Pivoted on the upper end of the shaft within the casing 65 and above the arm 71 is a horizontal starting lever 75, which has on its end outside the casing a handle 77 to be grasped by the right hand of the operator. This starting lever has rotatably mounted in it between its ends a vertical pin 79 with a notch 81 in the left side. The notch is so arranged that when the pin 79 is in one rotary position, the notch 81 will, when the starting lever 75 is moved rearwardly, receive the block 73, so the arm 71 will not be actuated. If the pin 79 is rotated slightly in a counterclockwise direction, as seen in Fig. 4, it will engage the block 73 upon movement of the starting lever. This will rotate the shaft 69 and cause the machine to be driven through the connections hereinbefore described. Secured on the pin 79 is a horizontal arm 83, which extends toward the left from the pin just above the starting lever 75. The arm, with the various appendages to be described, and the notched pin 79 by which the arm is pivoted, together furnish a clutch-governing device acting through the clutch-lever 67, 69, 71. At the outer 30 extremity of the arm 83 is a plate 85, the end of which is normally engaged by a hooked portion 84 of a substantially horizontal, forwardly extending bar 87. The rear end of the bar slides on the upper face of the starting lever and at its 35 forward end is connected by a universal coupling 89 to the upper end of an arm 91 mounted on a horizontal shaft 93 (Fig. 4) carried by a bracket 95 secured to the left side of the frame-arm. The arm 91 has formed with it an upwardly extending, controlling arm or hand-lever 97 arranged to be actuated by the left hand of the operator. The bracket 95, in which the rock-shaft 93 is mounted, has an upwardly extending portion or post 99 in front of the controlling lever, so that 40 the post and lever may be gripped by the operator to facilitate forward swinging movement of said lever. The controlling lever and bar 87, when the lever is released, are moved rearwardly by a spring-plunger 101 in the post 99, and their rearward movement is limited by an adjustable screw 103 threaded in a lug on the controlling lever and which engages the bracket 95.

50 The starting lever 75 is normally held in its forward position, against an unillustrated spring-plunger in the casing 65, by a spring 105 connected to the lever and to the casing. The hooked portion 84 of the bar 87 is urged into engagement with the plate 85 on the arm 83 of the governing device by a spring 107 connected to the bar and to the casing. The plate is held normally in its rearward position by a spring 109 stretched between a pin 111 on the starting lever and a pin on an extension 113 from the arm. A stop-face 115 formed on the arm 83 abuts against a lug 117 on the starting lever to limit rearward movement of the arm. The starting lever has pivoted on its upper face on a vertical stud 119 a detent or catch 121. Extending from this detent is a lug 123, normally held by a spring 127 against a projection 125 on the arm 83. When the pin 79 is rotated, as will hereinafter appear, to allow the machine to be started, the projection 125 moves away from the lug 123. The detent 121 is thereupon rotated by its spring 127, so that its 70

hooked end 129 is in a position to engage, when the starting lever 75 is moved rearwardly, a plate 131 secured on the bracket 64. This will retain the lever in its rearward position to cause the machine to continue in operation.

When the controlling lever 97 is in its rearward position, the hooked portion 84 on the bar 87 is behind the plate 85 on the arm 83. When the controlling lever is moved to its forward position by the left hand of the operator and the bar 87 is thereby carried forward, the notched pin 79 of the governing device is turned, by the engagement of the hook 84 with the plate 85, into such a position that when the starting lever 75 is thereafter shifted to the rear by the right hand of the operator, the pin will engage the block 73 on the arm 71. The shaft 69 thereupon will be rotated in a direction to cause the machine to be operated through the clutch mechanism previously described. If, however, the starting lever is moved rearwardly before the controlling lever 97 has been actuated, the shaft 69 will not be rotated, since the pin 79 will be in such a position that its notch will pass by the block 73, and the machine will not be operated. As the pin 79 is turned by the action of the controlling lever, the projection 125 on the pin-arm 83 releases the detent-lug 123 to allow the hooked end of the detent 121 on the starting lever to be swung clockwise by its spring 127. The resulting position is such that upon operating movement of the starting lever, the detent engages the plate 131 and holds said lever in operating position. This lever may then be released by the operator, and the machine will complete a single cycle and will be automatically stopped at the end of that cycle, as will hereinafter be described, provided the operator holds the controlling lever 97 in its forward position by his left hand. If, however, the controlling lever is released at any time during the operation of the machine, said lever and the bar 87 are moved rearwardly by the spring-plunger 101. This frees the arm 83 of the governing device and allows its pin 79 to be rotated by its spring 109 until the pin-notch 81 will receive the block 73, and the arm 71 upon the shaft 69 of the clutch-lever is moved by the spring 45 connected to the lever 33 through the notch. The shifting of said lever causes the pulley 13 to be unclutched from the driving shaft 5, and the machine is stopped by the application of the brake. When the arm 83 is thus turned with the pin 79, the projection 125, contacting with the lug 123, releases the detent 121 from the plate 131, and the starting lever 75 is moved forward by its spring 105 in readiness to cause again the operation of the machine. Since the pin 79 is now in such a position that movement rearwardly of the starting lever will not result in the rotation of the shaft 69 of the clutch-lever and the starting of the machine, the controlling lever must again be actuated to so position the pin that it will engage the block 73 when the starting lever is moved rearwardly. Under these conditions, the clutch-lever will then again be oscillated to cause the machine to start into operation.

It will therefore be seen that both hands of the operator require to be occupied in a position of safety well above the moving knife 135 to start the machine, and that the right hand of the operator may release the starting lever 75 as soon as it has been moved to the starting position. There is little danger of the operator, after releasing the starting lever, getting his hand where it would be injured by the knife or its supporting

mechanism. When the machine starts, the knife rapidly travels around the right-hand end of the blank being operated upon, and held between the pattern 137 and clamp 139, in a counterclockwise direction seen from above, toward the rear of the machine. By the time the right hand of the operator could be dropped on to the knife mechanism after having operated the starting lever, said knife will have traveled away from the region to which his hand would fall. The left hand of the operator must be occupied in holding the controlling lever 97 until the machine comes automatically to rest. This is desirable, since it is toward the end of the machine-cycle that the knife and its supporting mechanism travel around the left-hand end and along the front of the blank, and if the operator's left hand were free at this time, it might be lowered into a position where it would be injured by the moving parts. The free right hand of the operator may be utilized in preparing to supply another work-piece for the succeeding operation. The starting lever 75 and the controlling lever 97 are positioned substantially on the same level heightwise in the machine, and the starting lever is relatively close to the controlling lever, so that the two hands of the operator, when actuating said members, are held in a convenient position at a height somewhat below the level of the shoulders of a man of average height.

The mechanism for automatically stopping the illustrative machine at the end of a single cycle includes a cam 141 (Fig. 3) secured on the under side of the table 11, the outer edge of which cam, toward the end of the rotation of the table, engages a projection 143 rising from one arm 144 of a bell-crank-lever 145 pivoted on a vertical stud 147 fixed in a bracket secured to the machine-frame. The other arm 149 of the bell-crank-lever 145 has pivotally connected to it a rearwardly extending rod 151, which passes through an opening in a block 153 having a depending stem which is pivoted in an arm 155 secured to a vertical shaft 157 rotatably mounted in the bracket behind the stud 147. The rod 151 has fast on it a collar 159, which, when the bell-crank-lever 145 is turned by the cam 141, engages the block 153 and positively moves the arm 155 rearwardly. Surrounding the rod is a spring 161, which engages the block 153 and a collar 163 secured near the end of the rod. Attached to the shaft 157 near its upper end is an arm 165. Pivotedly connected to this arm is a forwardly extending rod 167, which is pivotally connected to an arm 169 (Fig. 4) of a bell-crank-lever 171 fulcrumed on a vertical stud 173 in the bracket 64. The arm 169 extends to the right, and a forwardly projecting arm 175 of the lever 171 has rising from it a pin 177. This pin is normally held in an inactive position by a spring 178 connected to the arm 165. It is positioned at the inner side of the rear end of the bar 87, and when the cam 141 on the table 11 swings the bell-crank-lever 145 rearwardly, the pin 177 so moves the bar as to disengage its hooked portion 84 from the plate 85 on the arm 83 of the governing device. The arm is then moved rearwardly by its spring 109, and the pin 79 is turned into a position in which its notch 81 allows the block 73 on the arm 71 to be moved by its spring 45 through the notch. The resulting shifting of the intermediate lever 33 causes the machine to be stopped, as already described.

As the table 11 arrives at its stopping position, the cam 141, under the influence of the momen-

tum of the parts, travels past the projection 143 on the lever 145, and the pin 177 is returned to its normal inactive position by the spring 178. As the table 11 is reversed in its rotation and returned to its normal position by the spring 52, the projection 143 rides along the inner edge of the cam 141, as appears in Fig. 3, the spring 161 being compressed as the rod is moved by the lever 145. The machine may then be again started by proper manipulation of the controlling and starting levers. If it were possible for the table to stop with the cam 141 holding the lever 145 in its rearward position, it would be impossible to again start the machine until the table had been rotated manually to move the cam away from the projection 143. The above-described arrangement, wherein the projection 143 on the lever engages the inner edge of the cam during the return movement of the table 11, insures that the machine may be started simply by manipulation of the levers after having been stopped by the cam.

To enable the table 11 of the illustrative machine to be turned manually if desired, the machine may have rotatable in a bracket secured to the right of the frame 1 below the table, a rearwardly extending shaft, which near its forward end has secured on it one member of a toothed clutch. Rotatable and slidable on the shaft at the front of the clutch member is a second member of the clutch, this having projecting from it a hand-lever by which the clutch may be engaged and the shaft rotated. Fast upon the rear end of the shaft is a sprocket-wheel 35 which is connected by a chain to a sprocket-wheel secured to the driving shaft 5.

The illustrative machine is provided with operator-controlled safety means, whereby the wedge 19 may be prevented from being moved in a direction to carry the pulley 13 on the driving shaft 5 into engagement with the driven member 17 when the controlling and starting levers are actuated by the operator. This means comprises a shaft 181 (Fig. 5) extending beneath the table 11 and rotatable at its forward extremity in a bearing on a bracket at the left of the frame 1 and at its rear end in a bearing on the bracket 3. The shaft 181 has secured on its forward end a hand-lever (not shown) by which the shaft may be actuated and has fixed to the opposite extremity a cam 183, which in one angular position engages an arm 185 depending from the wedge-lever 25 and holds the wedge 19 and wedge-bar 23 from upward movement to effect engagement of the clutch. In another angular position, the cam allows the wedge 19 to be shifted upwardly by its spring 43 when the controlling and starting levers are actuated. When the cam is in the former of the two positions, actuation of the controlling lever and the starting lever causes the brake to be released, and if the controlling lever 97 is held in its actuated position, the starting lever may be freed by the operator and his right hand used to rotate the table manually, as previously described.

The machine is further provided with stationary worktables 187 and 189 secured to the frame 1, respectively at the left and right of the rotary table 11. These tables 187 and 189 extend forwardly close to the forward edge of the table 11. The top of the table 187 is substantially at the level of the upper face of the rotary table and is about twenty inches from front to rear, so it extends almost as far rearwardly as the rotary table. It is about twelve inches from side to

side, the inner edge being curved about the axis of the table 11 and lying close to the periphery of a guard 191, surrounding the last-mentioned table. The table 187 has an upwardly extending wall 193 around its left, rear and front edges. The table 189 is substantially level with the top of the pattern 137 on which the blanks are clamped and is about thirty inches from front to rear and about twelve inches wide. Its inner edge extends around and close to the right side of the guard 191 and also rearwardly beyond the table 11. It has at its rear left corner a square, walled-off portion 195, forming a receptacle for tools, and an upstanding wall 197 is shown at its rear and right edges. The upper face of the guard 191 surrounding the table 11 is level with the upper face of the rotary table and consists of a narrow ring of right-angle section extending downwardly below the gear 9 to shield the operator from contact with said table. The guard is secured at its rear to the machine-frame by a horizontal spindle 199 extending laterally of the machine and passing through the frame and lugs upon the guard at each side of said frame. At the front, the guard may be supported by a bracket secured to the machine-frame.

The particular heightwise relation above described, of the rotary table and the two stationary tables at the opposite sides of the machine, facilitates the presentation of fresh work-pieces between the pattern 137 and its co-operating clamp 139 and the removal from the operating position of work-pieces which have been operated upon. This is true, since when the clamp is allowed to rise away from a trimmed work-piece on the pattern by release of its controlling treadle, the operator is able quickly, with his left hand, to slide the work-piece off the pattern toward the left with the knowledge that the piece will find its way on to the table 187 without falling off the table 11 toward the floor. Further, he can almost simultaneously carry a work-piece to be trimmed off the table 189 with his right hand, this piece being caused, by the fact that this table is substantially level with the upper face of the pattern, to slide on to the pattern without having to be lifted or lowered by the operator.

Having described our invention, what we claim as new and desire to secure by Letters Patent of the United States is:

1. In a rounding machine, a frame having an overhanging arm, a pattern mounted upon the frame, a clamp movable upon the arm in co-operation with the pattern, a knife movable about the pattern, driving mechanism by which the knife is moved, and two levers mounted upon the overhanging arm above the clamp for simultaneous engagement by the hands of the operator, both of which levers must be actuated to control the movement of the knife by the driving mechanism.

2. In a rounding machine, a frame having an overhanging arm, a pattern mounted upon the frame, a clamp movable upon the arm in co-operation with the pattern, a knife movable about the pattern, driving mechanism by which the knife is moved, and two levers mounted side by side at substantially the same height upon the overhanging arm and both movable by the operator in a direction longitudinal of the frame to cause the movement of the knife by the driving mechanism.

3. In a rounding machine, a frame having an overhanging arm, a pattern mounted upon the

frame, a clamp movable upon the arm in co-operation with the pattern, a knife movable about the pattern, driving mechanism by which the knife is moved and including a clutch, a controlling lever, a starting lever and a clutch-lever, all fulcrumed upon the frame above the clamp, the controlling lever governing the movement of the clutch-lever by the starting lever, and connections between the clutch-lever and clutch.

10 4. The combination with operating mechanism, of driving mechanism therefor, a device movable to govern the driving mechanism, two members for actuation by the operator, the movement of one member preparing the device for movement by the other, a catch movable upon one member, and relatively fixed retaining means which the catch engages.

15 5. The combination with operating mechanism, of driving mechanism therefor, a device movable to govern the driving mechanism, two members for actuation by the operator, the movement of one member preparing the device for movement by the other, a catch movable upon one member, relatively fixed retaining means which the catch engages, and means movable upon the member with the catch for determining the position of said catch.

20 6. The combination with operating mechanism, of driving mechanism therefor, a device movable to govern the driving mechanism, two members for actuation by the operator, the movement of one member preparing the device for movement by the other, a catch movable upon one member under the influence of the other member, and 25 relatively fixed retaining means which the catch engages.

25 7. In a rounding machine, a pattern, a knife movable about the pattern, driving mechanism for the knife, a starting lever for the driving mechanism and a controlling lever for the starting lever, both of which levers are movable by the operator, a retaining detent movable upon the starting lever, and a relatively fixed projection for engagement by the detent.

30 8. In a rounding machine, a pattern, a knife movable about the pattern, driving mechanism for the knife, a starting lever for the driving mechanism and a controlling lever for the starting lever, both of which levers are movable by the operator, a retaining detent movable upon the starting lever, a relatively fixed projection for engagement by the detent, and a lever fulcrumed upon the starting lever and acting upon the detent to vary its position.

35 9. In a rounding machine, a pattern, a knife movable about the pattern, driving mechanism for the knife, a starting lever for the driving mechanism and a controlling lever for the starting lever, both of which levers are movable by the operator, a retaining detent movable upon the starting lever, a relatively fixed projection for engagement by the detent, and a lever fulcrumed upon the starting lever and movable by the controlling lever to vary the position of the detent.

40 10. The combination with operating mechanism, of driving mechanism therefor including a clutch, a clutch-lever, a controlling lever and a starting lever each arranged for actuation by the operator, and a clutch-governing device having a space to receive the clutch-lever without effect upon it and arranged adjacent to the space for contact with said clutch-lever, said device being moved by the starting lever and movable upon said starting lever into clutch-lever-engaging position by the controlling lever.

45 11. The combination with operating mechanism, of driving mechanism therefor including a clutch, a clutch-lever, a controlling lever and a starting lever each arranged for actuation by the operator, and a clutch-governing device comprising a rotatable latch-pin and an arm pivoted at the latch-pin upon the starting lever, the governing arm being acted upon by the controlling lever to position the latch-pin and said latch-pin in certain positions engaging the clutch-lever.

50 12. The combination with operating mechanism, of driving mechanism therefor including a clutch, a clutch-lever, a controlling lever and a starting lever each arranged for actuation by the operator, a clutch-governing device arranged for contact with the clutch-lever, said device being moved by the starting lever and movable upon said starting lever into clutch-lever-engaging position by the controlling lever, and a catch for the starting lever movable by the governing device.

55 13. The combination with operating mechanism, of driving mechanism therefor including a clutch, a clutch-lever, a controlling lever and a starting lever each arranged for actuation by the operator, a clutch-governing device rotatable upon the starting lever between its ends and arranged for contact with the clutch-lever, said device being moved bodily by the starting lever and movable upon said starting lever into clutch-lever-engaging position by the controlling lever, and means actuated by the operating mechanism for shifting the governing device from such position.

60 14. In a rounding machine, a pattern, knife mechanism movable about the pattern, driving mechanism by which the knife mechanism is moved and including a clutch, a clutch-lever, a starting lever, a pin rotatable upon the starting lever and having a notch, said notched pin being arranged either to engage the clutch-lever or to pass it unaffected, a clutch-governing arm pivoted at the pin, and a controlling lever acting upon the clutch-governing arm.

65 15. In a rounding machine, a pattern, knife mechanism movable about the pattern, driving mechanism by which the knife mechanism is moved and including a clutch, a clutch-lever, a starting lever, a pin rotatable upon the starting lever and having a notch, said notched pin being arranged either to engage the clutch-lever or to pass it unaffected, a clutch-governing arm pivoted at the pin, a controlling lever, and a bar movable by the controlling lever and having a projection engaging the clutch-governing arm.

70 16. In a rounding machine, a pattern, knife mechanism movable about the pattern, driving mechanism by which the knife mechanism is moved and including a clutch, a clutch-lever, a starting lever, a pin rotatable upon the starting lever and having a notch, said notched pin being arranged either to engage the clutch-lever or to pass it unaffected, a clutch-governing arm pivoted at the pin, a controlling lever, a bar movable by the controlling lever and having a projection engaging the clutch-governing arm, and means for moving the bar to free the clutch-governing arm from the projection.

75 17. In a rounding machine, a pattern, knife mechanism movable about the pattern, driving mechanism by which the knife mechanism is moved and including a clutch, a clutch-lever, a starting lever, a pin rotatable upon the starting

- lever and having a notch, said notched pin being arranged either to engage the clutch-lever or to pass it unaffected, a clutch-governing arm pivoted at the pin, a controlling lever, a bar movable by the controlling lever and having a projection engaging the clutch-governing arm, and means movable by the knife mechanism for moving the bar to free the clutch-governing arm from the projection.
18. In a rounding machine, a pattern, knife mechanism movable about the pattern, driving mechanism by which the knife mechanism is moved through an operating cycle to its normal position, means controlling disconnection of the driving mechanism and permitting the knife mechanism to pass the normal position, and means for returning the knife mechanism to normal, said knife mechanism being provided with a portion effective during the forward movement to actuate the disconnecting means and ineffective for such purpose during the return movement.
19. In a rounding machine, a pattern, knife mechanism movable about the pattern, driving mechanism by which the knife mechanism is moved through an operating cycle to its normal

position, means including a lever controlling disconnection of the driving mechanism and permitting the knife mechanism to pass the normal position, and means for returning the knife mechanism to normal, said knife mechanism being provided with a cam arranged to contact with the lever at its opposite edges during the opposite movements of the knife mechanism.

20. In a rounding machine, a pattern, rotatable knife mechanism movable about the pattern, driving mechanism by which the knife mechanism is moved through an operating cycle to its normal position, means including two levers and a rod connecting the levers positively for movement in one direction and yieldably upon movement in the opposite direction, such means controlling disconnection of the driving mechanism and permitting the knife mechanism to pass the normal position, and means for returning the knife mechanism to normal, said knife mechanism being provided with a cam arranged to contact at its outer edge with one of the levers during the positive lever-connection and at its inner edge during the yieldable connection.
